UNITED STATES PATENT OFFICE.

DANIEL LEWIS LUDDINGTON, OF GRASS VALLEY, CALIFORNIA.

STOVE-DOOR.

SPECIFICATION forming part of Letters Patent No. 339,309, dated April 6, 1886.

Application filed September 16, 1885. Serial No. 177,940. (No model.)

To all whom it may concern:

Be it known that I, DANIEL LEWIS LUDDINGTON, a citizen of the United States, residing at Grass Valley, in the county of Nevada and State of California, have invented 5 certain new and useful Improvements in Stove-Doors; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

15 This invention has relation to improvements in doors for ovens of stoves, ranges, &c.; and it consists in the construction and novel arrangement of the same, all as will be hereinafter fully explained, and particularly pointed out 20 in the appended claim.

The annexed drawings, to which reference is made, fully illustrates my invention, in which Figure 1 is a front view of my device. Fig. 2 is a vertical section. Fig. 3 is a horizontal 25 sectional view, and Fig. 4 is a perspective view, of the cap.

Referring by letter to the accompanying drawings, A designates the oven-door, having the usual hinges, *a*, and knob *b*. This door 30 consists of a frame composed of sides *c* and a bottom, *d*, while the top is left free. These parts *c* and *d* are provided with grooves *e*, in which is arranged a glass plate, *f*, that serves

as a window, through which can be seen the meats, &c., within the oven, without opening 35 the oven-door. This glass plate slides in the grooves of the door-frame, and is removable therefrom at will, and, if broken, can be readily replaced by another. On the top of the door-frame is a cap plate, *g*, which is grooved, 40 as at *h*, to fit snugly over the top of said frame, and is closed at its ends to prevent endwise movement of the same. A perforation, *i*, is made through the door-frame, in order to permit a rod to be passed into the oven for changing 45 the position of the articles contained therein without opening the door for that purpose. It will be seen that the cap is removable, and when it is necessary to remove the glass the same can be readily accomplished and a new 50 glass inserted.

Having described my invention, what I claim, and desire to secure by Letters Patent, is—

The herein-described door for ovens, consisting of the frame provided with the grooves, adapted to receive the glass plate, the cap-plate having the longitudinal groove and closed ends, and removably applied to the frame, substantially as and for the purpose set forth. 55 60

In testimony whereof I affix my signature in presence of two witnesses.

DANIEL LEWIS LUDDINGTON.
